UNITED STATES PATENT OFFICE.

NIELS A. CHRISTENSEN, OF MILWAUKEE, WISCONSIN.

CARBURETOR.

Application filed March 1, 1924. Serial No. 696,199.

The invention relates to carburetors, and more particularly those operating under pressure.

The object of the invention is to provide a pressure-feed carburetor for starting systems for internal combustion engines of the type shown in my prior United States Letters Patents No. 1,185,874 of June 16, 1916, and No. 1,253,669 of January 15, 1918, and in my application Serial No. 453,798, filed March 19, 1921, said application Serial No. 453,798 having since the filing of this application issued as United States Letters Patent No. 1,517,533, on December 2, 1924. The invention further consists in the several features hereinafter set forth and more particularly defined by claims at the conclusion hereof.

In the drawings: Fig. 1 is a vertical sectional view taken on the line 1—1 of Fig. 3; Fig. 2 is a sectional view taken on the line 2—2 of Fig. 1; Fig. 3 is a plan view of the carburetor embodying the invention.

This carburetor is preferably now made as an individual unit, separate from the starter or compressor unit, and except for the valves, their seats and operating means and the nozzle, is of a single casting forming a casing designated generally by the numeral 4.

The casing has a float chamber 5, a fuel chamber or reservoir 6, an air passage 7 for compressed air, and a mixing passage 8 for compressed air and fuel formed therein.

The float chamber 5 has a float 9 working therein and controlling a needle valve 10 which controls the passage of fuel through a duct 11 in an inlet plug 12. This plug 12 has a threaded connection 14 with the float chamber top 13, removably secured to the casting. Liquid fuel is led from any suitable source through suitable piping to the tapped inlet 15 above the plug. A baffle cap 16 fits over the upper end of the plug and provides restricted communications 17 opening downwardly and registering with grooves 18 formed on the top of the plug 12 and communicating with the inlet to the duct 11 whereby foreign matter and impurities are prevented from passing to said duct. Impurities deposited in the annular space below the cap 16 may be removed from time to time by removing the top 13 and taking out the plug or cage 12. The needle valve

is limited in its upper movement by contact with its seat 19 and in its lower movement

by engagement of its flange 20 with a stop-screw 21 mounted on the plug. The chamber 5 is provided with the usual vent opening 22 and overflow therefrom indicates trouble.

Communication between the float chamber 5 and the reservoir 6 is through a passage 23 in a screw-plug 24, said passage being controlled by a check valve 25 closing toward said float chamber and in the form of a bolt having its head adapted to seat against the flat seat 25' of the plug 24, and its nut 26 serving as a stop to limit its movement but not preventing passage of fuel through said passage 23.

The air passage 7 has an upper horizontally disposed portion 26, a vertical portion 27 and a lower portion 28 adjacent the inlet end of the mixing passage 8.

A passage 29, threaded at its upper end, is provided between the fuel chamber 6 and the passage 7, and a removable fuel nozzle 30 has a threaded portion engaging the threaded portion of said passage. At its upper end this nozzle projects into the mixing passage and at its lower end said nozzle is provided with spaced slots 31 for engagement with a screw-driver or other suitable tool for the purpose of installation or removal, an assembly opening 32 being provided in the bottom and closed by a screw-plug 33.

An opening 34 provides a communication between the passage 7 and the chamber 6, to equalize the air pressure at the inlet to the passage 7 and the space above the fuel. The air pressure on the fuel in chamber 6 is slightly greater than that of the air in passage 7 adjacent the nozzle and this causes a feeding effect of the fuel at the nozzle.

For starting, the float permits of filling the chamber 6, as well as the lower end of passages 7 and 8, with liquid fuel, such as gasoline or other suitable fuel, up to a level indicated by the dotted line 35, which is more than sufficient for one operation of the starter.

With this construction, when compressed air is allowed to flow through the inlet 36 to the passage 7, its first effect is to pick up the fuel which has overflowed through the nozzle 30 into the lower end of the mixing tube, the part 28 and the lower part 27 of the passage 7, which parts form a temporary fuel reservoir, and carry this fuel along with it to a distributor, not shown, from which the

- mixture thus formed passes to the cylinders of the engine and after taking up the fuel in this temporary reservoir the continued flow of air through the passage 7 to the passage 8 draws the fuel out of the nozzle 30 and mixes this fuel with air in the passage 8. The check valve 25 prevents any back flow of fuel or air into the float chamber 5 when the compressed air is on.
- 10 The construction above described has the advantage of being simple and free from complicated operating parts, and is well adapted for the purpose described.
- What I claim as my invention is:
- 15 1. In a carburetor, the combination of a casing having a float chamber, a fuel reservoir, a compressed air passage and a mixing passage formed therein, a check-valve-controlled passage between said float chamber and reservoir, and a nozzle extending from said reservoir through a part of said air

passage into said mixing passage, said air passage having equalizing communication with the space above the fuel in said reservoir.

2. In a carburetor, the combination of a casing having a fuel reservoir, a mixing passage and a compressed air passage extending along the top of said reservoir and down to a space below the inlet to said mixing passage, said air passage having an opening in its upper portion into the upper part of said reservoir, a nozzle extending from said reservoir through said space below the inlet and into said mixing passage, and means for permitting initial filling said reservoir to a height above said nozzle whereby a temporary reservoir of fuel is formed in the lower parts of said air and mixing passages.

In testimony whereof I affix my signature.

NIELS A. CHRISTENSEN
